ALEXANDER MEISSNER, OF BERLIN, GERMANY, ASSIGNOR TO TELEFUNKEN GESELLSCHAFT FÜR DRAHTLOSE TELEGRAPHIE M. B. H., OF BERLIN, GERMANY, A CORPORATION OF GERMANY

CONVERTIBLE BAND PASS RECEIVER

Application filed February 18, 1931, Serial No. 516,586, and in Germany February 6, 1930.

The present invention relates to band pass receivers, and more particularly to a method of, and means for, operating a band pass receiver as a more sharply selective receiver.

5 In the operation of modern broadcast receiver sets it is necessary, on the one hand, that a large frequency range should be available (for instance, the sets must nearly always cover a range extending from 200 up to 800 meters) while, on the other hand, the band width must be constant throughout the whole frequency range. Since different broadcast transmitters are usually only about 10,000 cycles apart it follows that the frequency band admissible for the receiver amounts to only 10,000 cycles. Hence, the point is that, upon changing the wave of the receiver from 200 meters to, say, 600 or 800 meters, the accepted frequency band should 20 be 10,000 cycles throughout.

This requirement is not fulfilled with receivers of the kind heretofore known. The receivers have mostly been so built that alternately a tuned circuit and a tube followed 25 each other. But this insures merely greater selectance, in other words, greater tuning sharpness; the frequency band width changed from wave length to wave length. Indeed, for a constant inductive coupling adjustment, 30 it is so much larger the shorter the wave length. Now, this inconvenience may be obviated in the following manner.

Two tuned circuits, on the one hand, are in constant inductive coupling relationship, 35 while, on the other hand, they are coupled capacitively by a condenser which is invariable throughout the entire frequency range. The condenser is chosen so large that, in the presence of the high frequency for which 40 the tuning condensers are very small, it plays practically no part as regards the coupling between the two circuits, though playing a decisive part so far as the coupling at the lower frequency is concerned. It is thus possible to 45 create conditions so that for the whole frequency range the accepted frequency band width will remain substantially constant.

It has, heretofore, not been feasible to build a receiver which insured a constant band width, or channel, within relatively large

wave length ranges, with which therefore stations were received with constant band width, but which in the presence of disturbances could be altered so as to possess greater selectance and a narrower width.

Now, the solution of this problem, according to the present invention, resides in that a constant band pass receiver arrangement of the combined coupling type is provided with supplemental coupling means in the different tuning circuits. This coupling most suitably is insured by additional coils which are so linked that the coupling obtained by the constant band width is adapted to be compensated to zero partly or almost wholly, with the result that the different circuit systems act like very loosely coupled, and very selective, circuits.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 shows a pair of coupled tunable circuits of a conventional receiver and possessing a constant band pass characteristic,

Fig. 2 shows the circuit of Fig. 1 embodying the invention,

Fig. 3 shows a modified form of the invention.

Referring now to the drawing wherein like characters of reference in the different figures represent like elements, Fig. 1 shows a circuit scheme where L_1 , L_2 are the inductance coils comprised in a receiver operating with a constant band width. The mutual inductance between coils L_1 and L_2 is designated by M .

The tuning condensers C_1 and C_2 are variable; coupling condenser $C=14000$ cm; coils L_1 and L_2 have a diameter of 4 and a length of 6.5 cm, with 105 turns, the distance of the coils. For $\lambda=250$ m, then resulted in a frequency band of 18,500 cycles,

for $\lambda=400$ m., a frequency band of 20,000 cycles; and, at $\lambda=600$ m., a frequency band of 18,000 cycles. The space discharge devices 1 and 2 are coupled as well known in the art to any type of input, as an antenna, and to an output, as other tuned stages of amplification.

According to the present invention, and as shown in Fig. 2, supplemental coils l_1 , l_2 are inserted in each tuning circuit. These coils are so inter-coupled as at M' that their coupling may be made so strong that the coupling values resulting from the capacitive and inductive coupling of the two coils L₁, L₂ and condenser C can be reduced just to zero. Now, by any suitable mechanical means 3 the coupling between the two coils l_1 and l_2 can be reduced to zero; for instance, as by turning the coil faces in relation to each other any angle of 90 degrees.

Between the circuits there exists then only the coupling due to the inductances L₁ and L₂ and the condenser C; in other words, the constant band width. If from this position the counter-active coupling l_1 , l_2 be gradually introduced, then it will be possible to continuously adjust, or change, from constant band width to any desired band width of the receiver system so that, in the extreme case, the circuits act upon each other like two systems in very loose coupling relationship.

Instead of turning the coils l_1 , l_2 in relation to each other, the variation of coupling may be accomplished by shifting a copper slab between the two coils l_1 and l_2 , or using a short-circuiting ring. For example, in Fig. 3, there is shown a receiver system comprising several pairs of coupled tuned circuits, wherein the change in the auxiliary coupling between the tuned circuits may be effected simultaneously. In this figure, the copper plates C_u are mounted on a common shaft 4 and are shifted between the coils l_1 , l_2 as well as l'_1 , l'_2 and operated from a common knob H. The tubes 1, 2 and 2' are conventional. The tuning condensers C₁, C₂, C'₁, C'₂ may be operated by a common control 5.

While I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. In combination, a pair of tunable circuits each including a variable capacity and an invariable inductance, the inductances being coupled to provide magnetic coupling between the circuits, an untuned condensive reactance common to both circuits, said cou-

pled circuits possessing a constant band width characteristic throughout a given frequency range, and additional means common to both circuits for controlling the band width characteristic.

2. In combination, a pair of tunable circuits, each including a variable capacity and an invariable inductance, the inductances being coupled to provide magnetic coupling between the circuits, an untuned condensive reactance common to both circuits, said coupled circuits possessing a constant band width characteristic throughout a given frequency range, and additional means, including an auxiliary reactance in each circuit, common to both circuits for controlling the magnetic coupling between the circuits.

3. In combination, a pair of tunable circuits, each including a variable capacity and an invariable inductance, the inductances being coupled, an untuned reactance common to both circuits, said coupled circuits possessing a constant band width characteristic throughout a given frequency range, and additional means, including an auxiliary coupling coil in each circuit and a variable shield disposed between said auxiliary coils, for selectively varying the band pass characteristic to a sharply tuned characteristic.
